UNITED STATES PATENT OFFICE

135,210

DESIGN FOR A WEEDEER HEAD

Ernest P. Sokolis, Springfield, Ill.

Application September 24, 1942, Serial No. 108,332

Term of patent 7 years

To all whom it may concern:

Be it known that I, Ernest P. Sokolis, a citizen of the United States, residing at Springfield, in the county of Sangamon and State of Illinois, have invented a new, original, and ornamental Design for a Weeder Head, of which the following is a specification, reference being had to the accompanying drawing, forming part thereof.

I claim:

The ornamental design for a weeder head, as shown.

ERNEST P. SOKOLIS.
